OIL BURNER

Filed Sept. 15, 1930

UNITED STATES PATENT OFFICE

WILLIAM R. WINSELL, OF KANSAS CITY, MISSOURI

OIL BURNER

Application filed September 15, 1930. Serial No. 481,835.

My invention relates to oil burners, and has for its principal objects to promote complete vaporization of oil fed to the burner, to obviate formation of carbon within the 5 burner casing, and to provide for control of air supplied to the burner for supporting combustion of fuel.

In accomplishing these and other objects of my invention, I have provided improved 10 details of structure, the preferred form of which is illustrated in the accompanying drawing wherein:

Fig. 1 is a perspective view of an oil burner embodying my invention, an oil inlet pipe being shown fragmentarily.

Fig. 2 is an enlarged longitudinal section through the burner, illustrating the effect on fuel of the novel construction.

Fig. 3 is a section on the line 3—3, Fig. 2. Referring in detail to the drawing:

1 designates a casing or hollow body preferably cylindrical in cross section and curved longitudinally to provide an open air inlet end 2 having an axis adapted to extend horizontally, and a slightly upturned open outlet end 3. The casing curves downwardly from the inlet end and then upwardly to form the outlet, thus providing depressed upper and lower wall portions at points designated 4 and 5 substantially midway of the casing. Feet 6 and 7 comprising transverse wall-like bosses are formed on the casing for supporting the same in a predetermined position for a purpose presently disclosed.

35 The casing is provided with a side inlet 8 adjacent the top portion thereof, and spaced substantially from the edge of the open end 2, and a transverse plate or trough 9 having ends sealingly fixed to the sides of the casing to form a channel or chamber 10 is curved to form a trough-like shallow recess portion 11 to receive oil from the inlet. The front end edge portion 12 of the plate is flat, and extends toward the air inlet in a plane substantially tangential to the oil inlet, thus forming one edge of a mouth through which air may pass from the casing inlet through the chamber 10.

The front edge 13 of the trough is slightly 50 lower than the portion 12, to cause oil to

flow forwardly from the trough, and said edge is curved into oval form, whereby oil moving from the trough will flow over the surface of said edge to the curved lower face of the trough, and drip from the lowest portion thereof, as indicated at 14.

Located below the trough and inclined downwardly and forwardly is a plate 16 having ends sealingly attached to the casing, and extending a substantial distance forwardly from the trough. The rear edge of the plate 16 is located sufficiently rearward of the point 14 to assure reception of dripping oil by the plate, and the front edge extends substantially to the space in the casing defined by the depressed upper wall portion 4.

The delivery edge 17 of the plate 16 is formed oval to conduct oil to the lower margin of said edge for dripping therefrom.

A second transverse plate 18 inclined longitudinally of the casing oppositely to the inclination of the plate 16 has a front edge located slightly ahead of the front edge of the plate 16 and slightly below the extended plane of the lower face of said plate, to receive oil dripping from the plate 16 and conduct the oil rearwardly in the casing. The rear edge of the plate 18 has the oval formation.

A final member 19 of the series of inclined plates is inclined oppositely to the vertically adjacent plate 18, and has a front edge located substantially adjacent the point 5 representing the lowest place in the bottom wall portion of the casing.

Formed in the rear edge portion of the plate 19 and spaced rearwardly from the rear edge of the plate 18, is a transverse recess 20 forming a trough or well into which oil flowing from the plate 18 may pass, and a wick 21 consisting of asbestos or like absorbent material, preferably resistant to heat, is mounted in the recess to receive and hold oil and provide convenient means for initially igniting the fuel.

Air has access to the casing through the air inlet end 2 for supporting combustion of the oil, and air will pass freely through

the several passages defined by the trough and plates.

In order to control the air supply, I provide a damper including triangular leaves or vanes 23, 24 and 25 having inner ends mounted on a bolt 26 supported on the axis of the air inlet by an ear 27 extending from the casing. A spring 28 mounted on the bolt bears against the nut 29 thereon to urge the bolt head 30 into engagement with the leaves, whereby the vanes are frictionally latched to the ear 27 and may be moved rotatively to any desired positions to form and adjust the sizes and positions of air-admitting apertures in the air inlet end of the casing.

The outer ends of the vanes bear against and slide over a shoulder 32 formed in the inlet end of the casing.

20 A valved oil supply pipe 33 may be threaded in the oil inlet of the casing for delivering fuel to the burner.

25 In using the device, the legs 6 and 7 support the casing in such a position as to maintain the trough and plates horizontal and prevent lateral tipping of the casing, thus enabling the oil to flow evenly over the delivery edges of the trough and plates.

30 Oil delivered through the oil inlet will collect in the recess of the trough, and flow therefrom to drip from the lower face thereof to the plate 16.

35 Attention is called to the communicating relation between the trough chamber 10 and air inlet, whereby air is constantly supplied to the oil in the trough, and formation of carbon therein is thus avoided.

40 The oil will flow forwardly over the plate 16, and drip thence to the plate 18, to flow rearwardly in the casing and pass to the plate 19.

45 Upon initially setting up flow of fuel, oil passing to the plate 19 will tend to splash to the wick, and provide a body of oil that may be ignited to suitably heat the plates and set up vaporization of the fuel.

50 A fine mist or thick vapor will rise from each of the plates while the oil is flowing, which will be driven by the draft created by air moving from the air inlet through the several compartments into the flame formed at the front edges of the plates by the burning vapors.

55 The tubular casing curved as shown and provided with longitudinally inclined plates forming passages at the inlet end thereof, thus provides a combustion chamber portion adjacent the upturned outlet.

60 The damper vanes may be adjusted to provide a desired opening or group of openings for controlling inlet of air to the several passages, and are adapted to admit air to the upper passage or trough chamber 10 when any combustion supporting air is passing into the casing, due to the spacing of the front

edges of the plates from the air inlet end of the casing.

What I claim and desire to secure by Letters Patent is:

1. An oil burner including a casing having open inlet and discharge ends, an adjustable damper at said inlet end, an oil inlet in the casing, an upper arcuate transverse plate in said casing forming a trough in receiving relation with the oil inlet and having a rounded delivery edge tapering gradually into the lower surface of said arcuate plate to effect discharge of oil from the lowermost portion of the plate, a second forwardly declined plate for receiving oil dripping from the upper plate and having a front edge projecting into the casing beyond the front edge of the upper plate, a third forwardly inclined plate projecting into the casing beyond the front edge of the second plate for receiving oil therefrom, and a lower forwardly declined plate extending into the casing beyond the front edge of the third plate and receiving oil dripping from the rear edge of the third plate, each of said plates having unobstructed communication with said discharge end. 70

2. An oil burner including a casing having open inlet and discharge ends, an oil inlet in the casing, an upper arcuate transverse plate in said casing forming a trough in receiving relation with the oil inlet, a second forwardly declined plate for receiving oil dripping from the upper plate and located in the casing forwardly of the upper plate, a third forwardly inclined plate located in the casing below and forwardly of the second plate for receiving oil therefrom, a lower forwardly declined plate located in the casing below and forwardly of the third plate and having a recess and a wick in the recess in substantially receiving relation with the rear edge of the third plate, and an adjustable damper at said inlet end of the casing. 75

3. An oil burner including a casing having open inlet and discharge ends, an oil inlet in the casing, an upper plate having a transverse depression intermediate its front and rear edges to form a trough in receiving relation with said oil inlet and having a rounded front edge at a lower level than the rear edge and tapering gradually into the lower surface of said depression to effect discharge of oil from the lowermost portion of the plate, and a second forwardly inclined plate for receiving oil dripping from the upper plate and having a front edge projecting into the casing beyond the front edge of the upper plate. 90

4. An oil burner including a casing having open inlet and discharge ends, an oil inlet in the casing, an upper plate having a transverse depression intermediate its front and rear edges to form a trough in receiving relation with said oil inlet and having a rounded front edge at a lower level than the rear edge and tapering gradually into the lower surface of said depression to effect discharge of oil from the lowermost portion of the plate, and a second forwardly inclined plate for receiving oil dripping from the upper plate and having a front edge projecting into the casing beyond the front edge of the upper plate. 95

5. An oil burner including a casing having open inlet and discharge ends, an oil inlet in the casing, an upper plate having a transverse depression intermediate its front and rear edges to form a trough in receiving relation with said oil inlet and having a rounded front edge at a lower level than the rear edge and tapering gradually into the lower surface of said depression to effect discharge of oil from the lowermost portion of the plate, and a second forwardly inclined plate for receiving oil dripping from the upper plate and having a front edge projecting into the casing beyond the front edge of the upper plate. 100

6. An oil burner including a casing having open inlet and discharge ends, an oil inlet in the casing, an upper plate having a transverse depression intermediate its front and rear edges to form a trough in receiving relation with said oil inlet and having a rounded front edge at a lower level than the rear edge and tapering gradually into the lower surface of said depression to effect discharge of oil from the lowermost portion of the plate, and a second forwardly inclined plate for receiving oil dripping from the upper plate and having a front edge projecting into the casing beyond the front edge of the upper plate. 105

7. An oil burner including a casing having open inlet and discharge ends, an oil inlet in the casing, an upper plate having a transverse depression intermediate its front and rear edges to form a trough in receiving relation with said oil inlet and having a rounded front edge at a lower level than the rear edge and tapering gradually into the lower surface of said depression to effect discharge of oil from the lowermost portion of the plate, and a second forwardly inclined plate for receiving oil dripping from the upper plate and having a front edge projecting into the casing beyond the front edge of the upper plate. 110

8. An oil burner including a casing having open inlet and discharge ends, an oil inlet in the casing, an upper plate having a transverse depression intermediate its front and rear edges to form a trough in receiving relation with said oil inlet and having a rounded front edge at a lower level than the rear edge and tapering gradually into the lower surface of said depression to effect discharge of oil from the lowermost portion of the plate, and a second forwardly inclined plate for receiving oil dripping from the upper plate and having a front edge projecting into the casing beyond the front edge of the upper plate. 115

9. An oil burner including a casing having open inlet and discharge ends, an oil inlet in the casing, an upper plate having a transverse depression intermediate its front and rear edges to form a trough in receiving relation with said oil inlet and having a rounded front edge at a lower level than the rear edge and tapering gradually into the lower surface of said depression to effect discharge of oil from the lowermost portion of the plate, and a second forwardly inclined plate for receiving oil dripping from the upper plate and having a front edge projecting into the casing beyond the front edge of the upper plate. 120

10. An oil burner including a casing having open inlet and discharge ends, an oil inlet in the casing, an upper plate having a transverse depression intermediate its front and rear edges to form a trough in receiving relation with said oil inlet and having a rounded front edge at a lower level than the rear edge and tapering gradually into the lower surface of said depression to effect discharge of oil from the lowermost portion of the plate, and a second forwardly inclined plate for receiving oil dripping from the upper plate and having a front edge projecting into the casing beyond the front edge of the upper plate. 125

In testimony whereof I affix my signature.

WILLIAM R. WINSELL.
